UNITED STATES PATENT OFFICE.

ROBERT E. MITTON, OF SALT LAKE CITY, UTAH.

RUDDER-BAR RETAINER.

Application filed June 26, 1926. Serial No. 118,840.

My invention relates to aeroplanes and has for its object to provide a new and efficient rudder bar retainer.

A further object is to provide a new rudder bar retainer which may be set by the operator at any desired angle or in a direct line, and, after the retainer is set, the operator may remove his feet to rest them.

A still further object is to provide a rudder retainer which will make the operation of an aeroplane against a side wind much easier and safer than has heretofore been possible and one which will be easily operated and will not tire or tax the strength of the aviator. 10 These and other objects I accomplish with the device illustrated in the accompanying drawings in which similar numerals and letters of reference indicate like parts throughout the several views and as described in the 15 specifications forming a part of this application and pointed out in the appended claims.

In the drawings in which I have shown the best and most preferred manner of building my invention, Figure 1 is a front view of the 20 rudder bar of an aeroplane with my retaining device in place thereon. Figure 2 is a plan view of the same. Figure 3 is a plan view of the stand or support for the rudder bar and my retainer shown without the rudder bar in place. Figure 4 is a diagrammatic 25 plan view of the rudder bar and the rudder, with my retainer in place thereon. Figure 5 is a plan view of one of the pedals of my retainer. Figure 6 is a section on line 6-6 30 of Figure 5.

In the drawings I have shown the rudder bar of the aeroplane as A, on the ends of which bar the cables B, which operate the rudder C, are attached. A spider frame 1 35 is constructed and is centrally bored, as at 2, to receive the pivot bolt 3 of the rudder bar B. The said spider frame 1 is secured to the floor of the aeroplane and is braced by the extending flange D. The outer edge of 40 the said spider is made in the shape of two arcs E of a circle and racks 4 and 4' are secured on both sides of the spider arcs E. Levers 5 and 6 are secured to the rudder bar A by the pivot pins 7 which pass through one 45 corner of said levers and leave the other end of the said levers free to move. The said 50 levers 5 and 6 are made in one piece and are bent at right angles on the line 8, as shown in Figure 6, and again at right angles, as at 55 9, so that one portion 10 of said levers is parallel with the top portion 6'. An extended

lug portion 11 is provided on the extreme end of the portion 10 of said levers and has a dog or catch 12 on its extreme end thereof. When the said levers are secured to the rudder bar A by the pivot pins 7 the dogs 12 will be engaged with the teeth 13 on the racks 4 and 4'. Spring holding flanges 14 are provided on the other ends of said levers 5 and 6 and springs 15 and 16 are secured therein and have their other ends secured to the rudder bar A by the bar 17, which is secured to said rudder bar A and which is bored on its ends to receive the said springs. The said springs 15 and 16 when engaged in the flanges 14 and 60 the holes in the bar 17 hold the levers in the position shown in Figures 2 and 3 and hold the dogs 12 in engagement with the teeth 13 of the racks 4 and 4'. The pivot pins 7 pass through the upper and lower sides 6' and 10 of the said levers 5 and 6, as shown in Figures 6, so that the levers and dogs are pivoted 65 through the same point and the action of each is at the same time and is positive. Retaining flanges 20 are provided on the ends of the 70 levers 5 and 6 opposite the spring flanges 14 to keep the foot of the operator from sliding 75 therefrom.

The operation of my device is as follows: 80 When the operator of the aeroplane desires to set the rudder at any given or desired point, using his feet, he pushes the rudder bar A to the desired position and then releases his feet from the levers 5 and 6. When the feet are removed the springs 15 and 16 will draw 85 the levers toward the rear and the extended lugs 11, with their dogs 12, will be moved toward the racks 4 and 4'. The dogs 12 will engage with the teeth 13 on the said racks 4 and 4' and the rudder bar will be retained in 90 that position. Should it be necessary to change the position of the rudder the aviator will place his feet on the levers 5 and 6 and press them downwardly or forwardly and the dogs 12 will be disengaged from the teeth 13 95 on the racks and the rudder bar A may thus be moved to any desired position. Should there be a strong head wind from either side, the aviator will set the rudder bar A at such a position as will cause the aeroplane to go 100 forward in the desired direction and may then remove his feet from the rudder bar A. The dogs 12 will engage with the teeth 13 and the said rudder bar will be held in that 105 position. As the rudder bar A is connected with the rudder C by the cables B the rudder bar will at all times coact with the said rud-

der and the plane will be controlled as desired.

Having thus described my invention I desire to secure by Letters Patent and claim:

- 5 1. In a rudder bar retainer the combination of a rudder bar; a frame upon which said rudder bar is supported having an extended spider shaped framework formed thereon, on the outer and upper edge of which is pro-
- 10 vided an inwardly toothed rack segment on each side of the frame; bell crank foot operated levers pivoted on said rudder bar having dogs formed in the lower and inner side thereof adapted to engage with the toothed
- 15 racks on said supporting frame; an extension on the back side of said levers to which one end of a spring is secured; and springs engaged with said extensions and with said rudder bar to normally hold said dogs in said
- 20 toothed racks substantially as described.

2. In a rudder bar retainer the combination of a foot operated rudder bar pivotally mounted on a supporting frame and having the operating wires secured on the free ends thereof; inwardly projecting toothed racks 25 supported below and upon which the outer ends of said rudder bar are supported; pivoted levers on the arms of said rudder bar; dogs integral with said levers, and to be operated when said levers are pressed by the 30 operator, said dogs adapted to engage with the teeth on said racks; springs to normally hold said dogs in engagement with said racks when the operator's feet are removed from said levers and to press the dogs back into 35 engagement after the rudder bar has been operated and released.

In testimony whereof I have affixed my signature.

ROBERT E. MITTON.
